DINO SAMAIÀ, OF MILAN, ITALY

BOMB FOR USE WITH A SPECIAL BOMB-THROWER, OR WITH FIREARMS ALREADY EXISTING AND HAVING A SMALLER CALIBER THAN THE BOMB

Application filed May 6, 1929, Serial No. 360,954, and in Italy May 22, 1928.

The present invention relates to a bomb which can be thrown by a special bomb-thrower or also by firearms already commonly used, and of a smaller caliber than the bomb.

5 The bomb according to the invention utilizes the elastic force of the gases, in part and for a certain time, even after the bomb has left the barrel of the firearm.

10 One of the practical embodiments of the invention is illustrated, by way of example only, in the accompanying drawings in which:

Fig. 1 shows the bomb in longitudinal section.

15 Fig. 2 is an external view of the bomb.

Fig. 3 shows a cup-like sleeve in outside view and plan;

20 Fig. 4 is an outside view of a similar cup-like sleeve fitted with a tubular extension.

Fig. 5 is a section showing the bomb as loaded in a bomb-thrower.

Fig. 6 is a section of the cuplike sleeve (Fig. 3) as applied to a firearm.

25 Fig. 7 is a section of the cuplike sleeve fitted with tubular extension (Fig. 4) as applied to a firearm.

As may be seen from Fig. 1, the bomb comprises a bomb body —*a*— made up of a cylinder and two rounded ends. To the bottom rounded end a tail piece —*e*— is fixed; the top rounded end is provided with a recess in which the fuse —*b*— with its detonator —*c*— is screwed. At the point where the top rounded end joins the cylindrical portion of the bomb there is applied to the outside of the bomb a tube —*d*—, the inner diameter of which is a few millimeters in excess of that of the bomb body, the tube being kept

30 apart from the bomb by means of a ring —*d*—. The tube —*d*— is greater in length than the bomb body, has four wings —*f*— at its bottom end and some holes —*f*— at its top end, the purpose of these holes being ex-

plained herebelow. The upper portion of the tube may also be provided with a reinforcement consisting in a band —*d*—. The tube —*d*— should be adapted to be slid on a cup-like sleeve and be an easy fit thereon, 45 the sleeve forming an integral part of the

barrel in the case of the special bomb-thrower (Fig. 5) or being applied to the barrel at the movement of use when ordinary firearms are employed for launching the bomb.

With reference to the ordinary firearms, 55 if the barrel is of such a shape (tulip shape, for instance) that it can serve to retain the cuplike sleeve, the latter is formed with two half-rings —*i*— on which the sleeve proper —*h*— is screwed, the sleeve being mounted on the firearm in the manner indicated in Fig. 6. If on the contrary the firearm barrel does not lend itself for this purpose, the cuplike sleeve comprises, as indicated in Fig. 4, a tube —*l*— and the sleeve proper —*m*—. 60 As shown in Fig. 7, the tube —*l*— is inserted into the barrel of the firearm —*s*— from the breech end and then the sleeve —*m*— is screwed on the forward end of the said tube. 65 In this manner the sleeve cannot move in the 70 barrel.

Mode of working

On the launching charge deflagrating, the gases impinge against the tail-piece —*e*— 75 (Fig. 5) and a portion of them (due to the fact that the diameter of the tail piece is slightly less than the bore of the firearm, and due also to the inertia of the bomb) almost instantaneously go to impinge against the bottom calotte of the bomb, and then, through the small interstice left between the cylindrical bomb portion and the inside of the sleeve, go to impinge against the end ring —*d*— of the tube —*d*—.

80 As these gases, however, still possess a great pressure at the moment they reach the upper portion of the tube —*d*—, the reinforcement band —*d*— is provided in order to increase the mechanical strength of the tube, as well as the holes —*f*— in order to allow a certain portion of the gases to escape.

85 In this manner the gases, at the moment the bomb leaves its rest position, simultaneously act upon the bomb at all these points 90 and thus balance their propelling action.

95 The bomb thus acted upon leaves the firearm, but the gases are not at once free to expand in the air because a large portion of them is detained in the tube —*d*—; these 100

gases are obliged to continue to exert their propelling action on the bomb until the tube —*d*— will completely leave the sleeve —*p*—.

An auxiliary expansion chamber is thus formed for the gases, the gas force consequently being better utilized as well in respect to the duration as in respect to the greater regularity of the deflagration of the launching charge.

10 This latter function is performed also by the tail piece —*e*—, because when the bomb is slid on the firearm the tail piece occupies a certain space of the explosion chamber and thus reduces it to the correct volume. Moreover the tail piece, in conjunction with the bomb tube —*d*—, serves to guide the bomb during the time the tube is sliding inside the arm.

15 During its flight the bomb is maintained in the correct direction by the system built up of the tube —*d*— and four wings —*f*—.

Having now particularly described and ascertained the nature of my said invention and in what manner the same is to be performed, 20 I declare that what I claim is:—

1. A bomb for firearms of smaller caliber than that of the bomb itself, including a bomb body, a ring carried with the body near the outer end thereof, a tube carried by the ring 25 and surrounding the bomb in spaced concentric relation and projecting rearwardly from the body, the space between the body and tube being sufficient to accommodate the barrel of a firearm of proper caliber in order to allow the gases, on the explosion of the charge and before the inertia of the bomb has been overcome, of exerting their propelling action 30 against the ring so that the bomb may be acted upon by the gases from the beginning 40 and simultaneously for its entire length, this action being then continued when the bomb body has left the barrel of the firearm within the tube.

2. A bomb according to claim 1, wherein 45 by the expansion of the gases interposed between the bomb and the fire mouth on the explosion of the charge an elastic cushion is obtained which holds the bomb body in a coaxial position with regard to the firearm by 50 overcoming the tendency of the former to displace itself downwards by means of its own weight and in this manner overcoming the frictional contact between the bomb body and the lower portion of the fire-mouth.

3. A bomb according to claim 1, wherein 55 the tube forms a secondary shell for the bomb so that on the explosion of the internal charge of the bomb body, the bursting effect of the gases is considerably increased inasmuch as 60 these latter after having destroyed the walls of the bomb body, instead of being dispersed, destroy by their residual force the external tube so that the action of the bomb and its total effect are increased.

4. A bomb as claimed in claim 1 and in

combination with a firearm having its bore enlarged near the mouth to accommodate the bomb body, and a tail-piece projecting from the bomb and accommodated within the main part of the bore of the firearm, substantially as and for the purposes set forth.

5. The combination with a firearm, the outer end of the bore of which is enlarged to provide a chamber of a projectile including a bomb body seated in the chamber, a ring 75 fitted to the outer surface of the bomb body near the outer end thereof and resting against the outer edge of the firearm, a reinforced tube carried with the ring and arranged in spaced surrounding relation with the bomb 80 body and extending considerably therebeyond and slidably disposed on the outer surface of the firearm, a tail-piece on the inner end of the bomb body extending into the bore 85 and guide vanes arranged on the outer surface of the tube near the outer end thereof.

6. An arrangement as claimed in claim 5, wherein the tube is provided with a series of perforations near its point of juncture with the ring, substantially as and for the purposes set forth.

Signed at Milan Italy, this 25th day of April 1929.

DINO SAMAIA.
